(57) **CLAIM**

The ornamental design for a barbell collar, as shown and described.

DESCRIPTION

FIG. 1 is a front perspective view showing a new barbell collar;

FIG. 1A is a detailed view of the area identified in FIG. 1;
FIG. 1B is a detailed view of the area identified in FIG. 1;
FIG. 2 is a rear perspective view of the barbell collar of FIG. 1;

FIG. 2A is a detailed view of the area identified in FIG. 2;
FIG. 2B is a detailed view of the area identified in FIG. 2;
FIG. 3 is a front view of the barbell collar of FIG. 1;
FIG. 4 is a rear view of the barbell collar of FIG. 1;
FIG. 5 is a right-side view of the barbell collar of FIG. 1;
FIG. 6 is a left-side view of the barbell collar of FIG. 1;
FIG. 7 is a top view of the barbell collar of FIG. 1; and, FIG. 8 is a bottom view of the barbell collar of FIG. 1.

The broken lines in the drawings illustrate portions of the barbell collar that form no part of the claimed design.

1 Claim, 10 Drawing Sheets
